UNITED STATES PATENT OFFICE.

WILLIAM J. HULFORD, OF LAWRENCE, MASSACHUSETTS, ASSIGNOR OF TWO-THIRDS TO DANIEL F. FITZGERALD AND EVAN R. WILLIAMS, BOTH OF SAME PLACE.

INSULATING JACKET OR COVERING.

SPECIFICATION forming part of Letters Patent No. 396,933, dated January 29, 1889.

Application filed February 27, 1888. Serial No. 265,381. (No model.)

To all whom it may concern:

Be it known that I, WILLIAM J. HULFORD, of Lawrence, in the county of Essex, State of Massachusetts, have invented a certain new and useful Improvement in Insulating Jackets or Coverings, of which the following is a description sufficiently full, clear, and exact to enable any person skilled in the art or science to which said invention appertains to make and use the same, reference being had to the accompanying drawings, forming part of this specification, in which—

Figure 1 is a side elevation of a dinner-pail provided with my improved jacket or covering; Fig. 2, a like view showing certain modified details of construction, and Fig. 3 an enlarged vertical transverse section of a piece of the jacket.

Like letters and figures of reference indicate corresponding parts in the different figures of the drawings.

My invention relates to that class of jackets or coverings which are designed for keeping the contents of dinner or lunch pails warm by preventing the radiation of heat; and it consists in certain novel features, as hereinafter fully set forth and claimed, the object being to produce a simpler, cheaper, and more effective article of this character than is now in ordinary use.

The nature and operation of the improvement will be readily understood by all conversant with such matters from the following explanation.

In the drawings, A represents the body of the pail, B the cover, and C the bail, the body and cover being shown by dotted lines.

In the present instance a round or cylindrical pail is represented; but a pail of any suitable form, size, or construction may be used. The body D of the jacket is of suitable size and shape to fit the body A of the pail, over which it is drawn in use. The cover E of the jacket is also of suitable size and form to fit the cover B of the pail, and is provided with a downwardly-projecting annular flange, t, which passes down over the top of the body D when in position for use. Side slots or recesses, x, are formed in the flange t for the re-

ception of the bail C, and there is also an opening in the top of the cover E for the reception of the knob k of the cover B. Attached to the body D of the jacket there are elastic straps H, (see Fig. 1,) provided at their upper ends with triangular loops d. Attached to the corner of each of the flaps v of the cover E, formed by the slots x, there is a hook, z, adapted to engage the loops d.

In securing the cover E in position on the body D the loop d at each side of the pail is passed over the hooks z, and as the elastic straps H contract the cover will not only be drawn downward tightly onto said body, but the flaps v will be drawn toward each other by the action of the inclined sides a of the loops d on the hooks z, thereby causing the lower portion of the flange t to hug the body D closely and the heat to be retained more perfectly than would be the case if the cover were merely forced downward without having the flaps v drawn together.

Instead of using elastic straps H, inelastic straps may be employed, said straps being divided and provided with buckles to exert a strain on the loops d, if preferred. An eye 75 in which the loop d is inserted may also be employed instead of one of the hooks z when a buckle is used in the strap H, if desired.

I sometimes provide the body D, as shown in Fig. 2, with vertical loops g, and the flaps v with straps h and buckles r, said straps being inserted in said loops and the flaps drawn together and secured by the straps and buckles, the loops and straps also serving to attach the cover E and body D to each other.

The outer portion of the jacket is composed of rubber cloth or similar water-proof material, i, which is lined with flannel, felt, or similar non-conducting material, w.

It is well known that in transporting pails of this character they are frequently exposed to rain, which evaporates on striking them, and thereby rapidly cools their contents. The water-proof material i is designed to obviate this, and fully accomplishes the purpose for which it is employed.

In the drawings but one side of the pail is shown and one set of fasteners for attaching

the cover of the jacket to its body; but it will be understood that the jacket is provided with a corresponding set of fasteners at the opposite side of the pail, and that the cover E has 5 two slots, *x*, standing opposite each other.

Having thus explained my invention, what I claim is—

1. In a jacket or covering of the character described, the insulating-cover E, having the 10 flaps *v v*, provided with the hooks *z*, in combination with the insulating-body A, provided with the loops *d*, and means, substantially as described, for exerting a strain on said loops when engaged with said hooks, sub- 15 stantially as set forth.

2. The insulating-body A, having the elas-

tic straps H, provided with triangular loops *d*, in combination with the insulating-cover E, having the side slots or recesses, *x*, forming flaps *v*, said cover being provided with hooks 20 *z*, substantially as described.

3. In a jacket of the character described, the insulating-cover E, having side slots or recesses forming flaps *v*, said flaps being provided with hooks, in combination with the insulating-body A, provided with a loop for receiving said hooks, whereby the flaps may be drawn together, substantially as described. 25

WILLIAM J. HULFORD.
